2 Sheets-Sheet 2

A technical drawing of a mechanical assembly, likely a cylinder or valve, with various numbered components. The drawing is oriented vertically. Key features include:

- A top cap with a central hole and a ribbed side.
- A central vertical rod with a flared top and a flange with a central hole.
- Two sets of horizontal lines representing piston rods, each with a flared end.
- Numbered callouts pointing to specific parts:
  - 11: Bottom left, a vertical line.
  - 12: Top right, a vertical line.
  - 13: Middle right, a vertical line.
  - 14: Middle left, a vertical line.
  - 15: Middle right, a vertical line.
  - 16: Middle left, a vertical line.
  - 17: Middle right, a vertical line.
  - 18: Middle left, a vertical line.
  - 19: Middle right, a vertical line.
  - 20: Middle left, a vertical line.
  - 21: Middle right, a vertical line.
  - 22: Middle left, a vertical line.
  - 23: Middle right, a vertical line.
  - 24: Middle left, a vertical line.
  - 25: Middle right, a vertical line.
  - 26: Middle left, a vertical line.
  - 27: Middle right, a vertical line.
  - 28: Middle left, a vertical line.
  - 29: Middle right, a vertical line.
  - 30: Middle left, a vertical line.
  - 31: Middle right, a vertical line.
  - 32: Middle left, a vertical line.
  - 33: Middle right, a vertical line.
  - 34: Middle left, a vertical line.
  - 35: Middle right, a vertical line.
  - 36: Middle left, a vertical line.
  - 37: Middle right, a vertical line.
  - 38: Middle left, a vertical line.
  - 39: Middle right, a vertical line.
  - 40: Middle left, a vertical line.
  - 41: Middle right, a vertical line.
  - 42: Middle left, a vertical line.
  - 43: Middle right, a vertical line.
  - 44: Middle left, a vertical line.
  - 45: Middle right, a vertical line.
  - 46: Middle left, a vertical line.
  - 47: Middle right, a vertical line.
  - 48: Middle left, a vertical line.
  - 49: Middle right, a vertical line.
  - 50: Middle left, a vertical line.
  - 51: Middle right, a vertical line.
  - 52: Middle left, a vertical line.
  - 53: Middle right, a vertical line.

The drawing is labeled "Fig. 5" in the bottom right corner.

UNITED STATES PATENT OFFICE

2,361,510

FIREARM

Raymond G. Stout, Wilkes-Barre, Pa.

Application September 16, 1942, Serial No. 458,543

6 Claims.

(Cl. 42—42)

This invention relates to firearms of the double-barreled single trigger type, one of the objects being to provide a trigger mechanism which enables the user of the firearm to fire either barrel first and, by a second pull on the trigger, to fire the remaining barrel, this order of firing continuing at the will of the user and without danger of the unintentional discharge of the second barrel upon the discharge of the first.

A further object is to provide a trigger mechanism which can be used in connection with an automatic safety such as renders the gun safe while loading and unloading, it being possible to render the gun "safe" after the discharge of one barrel only if desired and without interference with the perfect functioning of the firearm or its safety mechanism.

A still further object is to provide a single trigger double-barreled gun which can be used as safely as the standard two-trigger gun.

Another object is to provide trigger mechanism which is of such simplicity in design as to permit manufacture of the parts readily and at low cost, all of the parts being of sturdy construction and capable of functioning properly for the life of the firearm.

A still further object is to provide a firearm utilizing selective means located where immediate selectivity is made possible.

An object is to provide a double-barreled single trigger firearm which does not alternate in firing but continues to fire first at all times the barrel to which it has been set.

A further object is to provide a trigger which has the same length of pull for each barrel and does not shift its position after one barrel has been fired.

A still further object is to provide a trigger which is not set by recoil but is purely mechanical throughout, it being possible to set the trigger for choice of barrels either before or after firing, and also enabling the user to operate the trigger whether or not the gun is loaded.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a longitudinal section through a portion of a gun equipped with the present improvements, some of the parts being shown by full and dotted lines in two different positions respectively.

Figure 2 is a section on line 2—2, Figure 1.

Figure 3 is a section on line 3—3, Figure 1.

Figure 4 is a view partly in section and partly in elevation showing the trigger, the sear lift and the recoil block, the same being set to actuate the right sear.

Figure 5 is a plan view of the parts positioned as shown in Fig. 4.

Figure 6 is a side elevation of these parts showing the sear lift and recoil block in their rear positions due to the recoil resulting from firing of the right barrel.

Figure 7 is a perspective view of the trigger and the parts carried thereby with the sear lift shifted to actuate the left sear first.

Referring to the figures by characters of reference, 1 designates a portion of a firearm structure having hammers 2 and 3 each of which is adapted to be held cocked by a sear. One of 25 these sears is provided with each hammer as indicated at 4 and 5, the sears being pivotally mounted at 6 and being yieldingly held at one end in hammer-engaging position by springs 7.

The sears are provided at their rear ends with 30 laterally extended fingers 8 and 9 respectively which are oppositely disposed and extended toward each other.

The trigger 10 is pivotally mounted at 9 and is held yieldingly in lowered or normal position by 35 a spring 11 thrusting upwardly against a bracket 12. The upper surface of the trigger is flat to provide a supporting base 13 and the movement of the trigger is limited by a shoulder 14 and an extension 15, these being spaced apart a distance 40 sufficient to permit the necessary movement of the trigger.

A transverse slot 16 extends downwardly into the trigger and has a rounded enlarged lower end 17. In this slot is slidably mounted a flat 45 tongue 18 having an enlargement 19 slidably seated in the enlarged portion 17 of the slot. Spaced notches 20 are provided in this enlarged or rounded portion 19 of the tongue and either of these notches is adapted to receive a ball 21 50 against which is seated a spring 22 which, as shown particularly in Fig. 4, is held in a bore 23 by a screw plug 24. Buttons 25 are connected to and extended in opposite directions from the enlargement 19 and by means thereof the tongue 55 18 can be pressed laterally within the slot 16,

ball 21 serving to hold these shiftable parts in either of two extreme positions, as will be apparent.

Tongue 18 extends downwardly from and can be made integral with a post 26 which is slidable on the top or bearing surface 12 of the trigger and its extension 14, and extending through the post from front to rear at the center thereof is a bore 27 the forward end of which is counter-bored as shown at 28.

A recoil block 29 is slidable on extension 14 and is connected by a bar 30 to a sear lift which is indicated generally at 31 and is slidably mounted on the surface 12 of the trigger. Bar 30 is slidable in the bore 27 and the counterbore 28 holds a coiled spring 32 which thrusts constantly against the sear lift 31.

The sear lift includes a flat base 33 and an upstanding wing 34 integral therewith, the base and wing being connected at the center by a triangular flange 35 having an upwardly and rearwardly inclined advancing surface. A tongue 36 projects forwardly from the middle portion of the base 33.

The fingers 6 and 7 of the sears are extended into the path of the sear lift and said lift is normally located as shown in Fig. 4 so that by pushing either one of the buttons 25, the lift 31 can be pushed to the right or to the left. Should it be desired to fire the right barrel of the gun before the left barrel is fired, the user presses the post 26 toward the right. This will bring the inclined forward surface of the flange 35 into position back of the finger 6 of the right sear, and the tongue or lug 36 will be extended under the finger 6 as shown in Figure 5. Thus when the trigger 8 is pulled the finger 6 will be caused to ride upwardly along the inclined surface of the flange 35, thereby disengaging sear 4 from its hammer 2 before sear 5 can be disengaged. The discharge of the right-hand barrel thus produced will cause a recoil as shown in Figure 6 which will drive the sear lift 31 and block 29 backwardly against the action of spring 32 so that there will be no possibility of accidentally lifting the left-hand sear. Thereafter when the parts are returned to their normal positions by spring 32 and the trigger is again pulled, the finger 7, which is normally supported at a lower level than the finger 6, as shown in Fig. 6, will be lifted by that portion of the base 33 at the left of flange 35 from the full line position shown in Fig. 1 to the dotted line position or until the left-hand hammer has been tripped and the left-hand barrel has been fired.

As long as the sear lift remains in the position to which it was first adjusted, the right-hand barrel will always be fired in advance of the left-hand barrel. However should it be desired to fire the left-hand barrel first, it becomes merely necessary to shift the block 26 to the left, thereby to bring the flange 35 into position where it will engage the finger 7 of sear 5 so as to actuate that sear before the base 31 can lift finger 6 of sear 4.

Importance is attached to the fact that the action of the recoil block serves entirely to disconnect the sear lift from the sears upon the rebound of the gun. Thus unintentional discharge of the second barrel is prevented while the trigger is being pulled to discharge the first barrel. Furthermore if the trigger is not entirely released, the sear lift will not go forward under the second sear and cause unintentional discharge of the second barrel.

Obviously the trigger can be made non-selective simply by locking the recoil post in a fixed position and eliminating the selective buttons, should that construction be preferred by the manufacturer or the user.

By shifting the safety 37 into position above the post 26 the trigger will be held against movement.

What is claimed is:

- 10 1. The combination with a double-barreled firearm structure including separate hammers, of laterally spaced sears for the respective hammers, a trigger pivotally mounted in the structure, a sear lift carried by the trigger and mounted for backward sliding movement under the action of the recoil of the gun when fired, a post 15 slidable on the trigger and constituting a guide for the lift and means under the control of the user for shifting the post and lift laterally relative to the trigger into position to initially actuate a selected sear.
- 20 2. The combination with a two-barreled gun structure including separate hammers, of a sear for each hammer, said sears being laterally spaced, a trigger movably connected to the gun structure, a recoil actuated sear lift carried by the trigger and including means for successively lifting the sears during successive actuations of the trigger, a post 25 shiftable laterally on the trigger, means movable with the lift and cooperating with the post for guiding the lift when shifted by the recoil, and means under the control of the user for shifting the post and the sear lifting means laterally relative to the trigger into position to lift either sear in advance of the other sear during successive actuation of the trigger.
- 30 3. The combination with a two-barreled gun structure and separate hammers for the respective barrels, of a sear for each hammer, each sear having a laterally extended portion, and selective means carried by and shiftable relative to the trigger for actuating either of the sears in advance of the other sear during successive actuations of the trigger, said selective means including a post 35 shiftable transversely on the trigger, a base mounted to slide on the trigger under the action of recoil and extended under the laterally extended portions of the sears, means connected to the base and cooperating with the post to guide the base during recoil action, an inclined portion on the base, and means under the control of the operator for shifting the post laterally relative to the trigger to correspondingly move the base to position its inclined portion to lift either sear in advance of the other sear.
- 40 4. The combination with a two-barreled gun structure and separate hammers for the respective barrels, of a sear for each hammer, each sear having a laterally extended portion, and selective means carried by and shiftable relative to the trigger for actuating either of the sears in advance of the other sear during successive actuations of the trigger, said selective means including a post 45 shiftable laterally upon and movable with the trigger, a recoil block, a base, a rod connection between the block and base and shiftable within the post, said base and block shiftable on the trigger, yielding means carried by the rod for resisting movement of the base by recoil action, said base being extended under both sears, an inclined portion carried by an intermediate portion of the base, and means under the control of the operator for shifting the post laterally to position the inclined portion to lift
- 50 5. The combination with a two-barreled gun structure and separate hammers for the respective barrels, of a sear for each hammer, each sear having a laterally extended portion, and selective means carried by and shiftable relative to the trigger for actuating either of the sears in advance of the other sear during successive actuations of the trigger, said selective means including a post 55 shiftable laterally upon and movable with the trigger, a recoil block, a base, a rod connection between the block and base and shiftable within the post, said base and block shiftable on the trigger, yielding means carried by the rod for resisting movement of the base by recoil action, said base being extended under both sears, an inclined portion carried by an intermediate portion of the base, and means under the control of the operator for shifting the post laterally to position the inclined portion to lift
- 60 6. The combination with a two-barreled gun structure and separate hammers for the respective barrels, of a sear for each hammer, each sear having a laterally extended portion, and selective means carried by and shiftable relative to the trigger for actuating either of the sears in advance of the other sear during successive actuations of the trigger, said selective means including a post 65 shiftable laterally upon and movable with the trigger, a recoil block, a base, a rod connection between the block and base and shiftable within the post, said base and block shiftable on the trigger, yielding means carried by the rod for resisting movement of the base by recoil action, said base being extended under both sears, an inclined portion carried by an intermediate portion of the base, and means under the control of the operator for shifting the post laterally to position the inclined portion to lift
- 70 7. The combination with a two-barreled gun structure and separate hammers for the respective barrels, of a sear for each hammer, each sear having a laterally extended portion, and selective means carried by and shiftable relative to the trigger for actuating either of the sears in advance of the other sear during successive actuations of the trigger, said selective means including a post 75 shiftable laterally upon and movable with the trigger, a recoil block, a base, a rod connection between the block and base and shiftable within the post, said base and block shiftable on the trigger, yielding means carried by the rod for resisting movement of the base by recoil action, said base being extended under both sears, an inclined portion carried by an intermediate portion of the base, and means under the control of the operator for shifting the post laterally to position the inclined portion to lift

either sear in advance of the other sear during successive actuations of the trigger.

5. In a firearm the combination with a trigger, of means thereon for successively tripping separate sears and for actuating either sear in advance of the other sear, said means including a post mounted for transverse sliding movement on the trigger, means for shifting the post in either direction transversely of the trigger, a recoil block slideable on the trigger, a lifting member slideable on the trigger, a connection between the block and lifting device slideable in the post, yielding means for resisting movement of the block and lifting device in one direction relative to the post, said lifting device including means controlled by the transverse shifting of the post relative to the trigger for lifting a selected sear in advance of the other sear.

6. In a firearm the combination with a trigger,

of means thereon for successively tripping separate sears and for actuating either sear in advance of the other sear, said means including a post mounted for transverse sliding movement on the trigger, means for shifting the post in either direction transversely of the trigger, a recoil block slideable on the trigger, a lifting member slideable on the trigger, a connection between the block and lifting device slideable in the post, yielding means for resisting movement of the block and lifting device in one direction relative to the post, said lifting device including a base extending under the sears, an inclined flange upstanding from the base, and means for shifting the post laterally in either direction to position the flange to actuate either sear in advance of the other sear.

RAYMOND G. STOUT.
